CLAIM

We claim, the ornamental design for a tracker motor support for truss foundations, substantially as shown and described.

DESCRIPTION

FIG. 1 is a top right perspective view of a tracker motor support for truss foundations showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed lines in the figures show portions of the tracker motor support for truss foundations that form no part of the claimed design.
